Primary Examiner — Wan Laymon

(57) **CLAIM**

The ornamental design for an electrosurgical cutting forceps, as shown and described.

DESCRIPTION

FIG. 1 is a perspective view of the device;
FIG. 2 is a perspective view of the device;
FIG. 3 is a front elevational view of the device;
FIG. 4 is a back elevational view of the device;
FIG. 5 is a right side elevational view of the device;
FIG. 6 is a left side elevational view of the device;
FIG. 7 is a top view of the device; and,
FIG. 8 is a bottom view of the device.

In the drawings, the broken lines depict environmental subject matter and form no part of the claimed design.
